George Augustus Scott Inventor

By his Attorney G. J. Gordon

UNITED STATES PATENT OFFICE.

GEORGE AUGUSTUS SCOTT, OF NEW YORK, N. Y.

DESIGN FOR A CURLING AND CRIMPING COMB.

SPECIFICATION forming part of Design No. 18,787, dated December 4, 1888.

Application filed October 20, 1888. Serial No. 288,718. Term of patent 7 years.

To all whom it may concern:

Be it known that I, GEORGE AUGUSTUS SCOTT, a citizen of the United States, residing in the city of New York, county and State of New York, have invented and produced a new and original Design for Curling and Crimping Combs, of which the following is a specification.

The nature of my design is fully represented in the annexed drawing, which is a front view of my curling and crimping device.

The leading feature of my design is the configuration of the comb proper and the handle thereof, the handle a trifle shorter than the shank and comb combined, but both of rounded form and circumferentially depressed near their junction, the handle once and the shank twice. The comb-section is divided into eighteen teeth, the spaces be-

tween being one-third, or thereabout, wider than the intervening teeth, and the upper parts of each end tooth widened to taper, one toward the extreme end of the shank and the other more markedly toward the first depression thereof.

What I claim as my invention is—

A design for a curling and crimping comb having a round handle and shank, the former with one the latter with two depressions near their intersection, the handle and comb parts nearly equal in length, and the comb-section round-backed and divided into teeth spaced and tapered substantially as described and shown.

GEO. AUGUSTUS SCOTT.
